UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

VOLTMETER.

Application filed May 15, 1924. Serial No. 713,439.

My invention relates to voltmeters and particularly to voltmeters of the corona-discharge type for relatively high voltages.

The object of my invention is to provide a voltmeter that shall be capable of measuring voltages over a wide range by means of corona discharge.

It is well known that, as the potential between two conductors is raised, a visible corona discharge is produced at the surface of one conductor when the voltage gradient at the surface of this conductor is sufficiently great. For a given air pressure and temperature, the critical value of the voltage gradient is definitely fixed within narrow limits so that the discharge may be utilized in a voltage-measuring instrument.

In order to obtain an instrument which would cover a range of voltages,—that is, form a corona discharge for any one of the several voltages,—it has been proposed to enclose the conductor in a suitable container and vary the temperature or pressure of the surrounding medium. This is a rather troublesome method and requires complicated apparatus.

Since the corona discharge is a function of the voltage gradient, it has also been proposed to construct an instrument covering a range of voltages by employing conductors of different sizes or a tapered conductor, as disclosed in U. S. Patent No. 1,289,068, issued December 31, 1918, to C. T. Allcutt and assigned to the Westinghouse Electric & Mfg. Company. The first mentioned arrangement was found undesirable because of the necessity for substituting different conductors and because the employment of conductors of different sizes permitted voltage readings only in steps. The latter device described in the Allcutt patent is rather complicated as it requires a shield for the tapered conductor.

It is the object of my invention to provide a simpler but equally effective corona voltmeter that will read directly over a range of voltages by corona discharge. I obtain this result by employing two relatively movable conductors so arranged that varying the relationship of the conductors varies the voltage gradient upon the corona-forming conductor and thereby changes the required applied

voltage for producing the corona discharge.

In the preferred embodiment of the invention, one of the conductors is pivotally mounted upon an eccentric axis and carries a pointer co-operating with a fixed scale to show the angular position of the movable conductor and the corresponding applied voltage required to initiate corona discharge. The formation of corona is indicated by an ammeter connected in series with the corona voltmeter, a sharp deflection of the ammeter being obtained upon the formation of the corona discharge.

The detailed construction and the mode of operation of my invention will be apparent from the accompanying drawings wherein

Figure 1 is a plan view of one modification thereof, and

Fig. 2 is a side view of the same instrument. 70
1 represents a conductor, the potential of which it is desired to determine. Surrounding the conductor 1 is a hollow cylindrical conductor 2, having insulated flared ends 3 to produce a uniform electro-static field. 75 The conductor 2 is pivotally mounted upon an eccentric axis 4 and is provided with a pointer 5. As the conductor 2 is turned about the axis 4, the pointer 5 indicates its angular position upon the scale 6. A current-measuring instrument 7, which may be of the D'Arsonval type, is connected to the conductor 2.

The operation of the device is as follows:

In order to measure the potential of the conductor 1, the movable conductor 2 is turned about the axis 4 from its initial position shown until a sharp deflection of the ammeter 7 indicates that corona discharge has been formed between conductors 1 and 2. At this point, the pointer 5 indicates the potential of the conductor 1, the scale 6 being preferably calibrated to read voltages directly.

It will be apparent, that as the conductor 2 is rotated about the axis 4, a part of the surface of conductor 2 is brought nearer to the conductor 1, thereby increasing the voltage gradient at the surface of the latter. This voltage gradient is increased by the movement of the conductor 2 until corona forms upon the conductor 1. As we have seen, for a

given pressure and temperature, the formation of corona depends solely upon the voltage gradient. Therefore, the angular position of the conductor 2, as indicated by the 5 pointer 5, provides a direct indication of the potential of conductor 1.

I claim:

1. A voltmeter operable by means of corona discharge comprising normally concentric 10 conductors having opposed cylindrical surfaces, one of said conductors being movable about an eccentric axis.
2. In combination, two normally concentric conductors one of which is rotatively supported upon an eccentric axis, and a corona-discharge-indicating device connected to one 15 of said conductors.
3. In combination, a stationary conductor, a movable conductor encircling said stationary conductor, means for changing the distance 20 between the movable and the stationary conductors, means for indicating an electrical phenomena between said conductors, and means associated with said movable con-

ductor for indicating the voltage producing 25 said phenomena.

4. An electrostatic voltage-measuring system comprising a stationary elongated conductor, a hollow cylindrical conducting body encircling said conductor, said body being 30 movable about an eccentric axis with respect to said conductor whereby the distance between the body and the conductor may be changed, means for indicating the formation of corona between said body and said conductor, and a scale associated with said movable body for indicating the magnitude of the voltage producing said corona.

5. An electrostatic voltmeter comprising normally concentric conductors, means for 40 indicating the formation of corona between said conductors, and means for varying the distance between said conductors to cause the formation of corona.

In testimony whereof, I have hereunto subscribed my name this 28th day of April, 1924.

CHARLES LE G. FORTESCUE.
